UNITED STATES PATENT OFFICE.

WALTER W. KOHLER, OF LEXINGTON, NEBRASKA.

GAME APPARATUS.

No. 854,581.

Specification of Letters Patent.

Patented May 21, 1907.

Application filed February 16, 1907. Serial No. 357,725.

To all whom it may concern:

Be it known that I, WALTER W. KOHLER, a citizen of the United States of America, residing at Lexington, in the county of Dawson 5 and State of Nebraska, have invented new and useful Improvements in Game Apparatus, of which the following is a specification.

This invention relates to a game apparatus, 10 and one of the principal objects of the same is to provide a game which will be both amusing and entertaining, and will require considerable skill on the part of the players to become proficient in playing the game.

Another object of the invention is to provide a game of the pin-pool type in which the accessories are a number of pins, each having a predetermined value, and a plurality of balls of differing colors also having a certain 20 value, and a central pocket in the game board into which the balls may be rolled thence into a chance trough or runway underneath the board which will convey the balls to one or the other of the players, depending upon chance.

Still another object of the invention is to provide a game board which can be quickly taken apart and reassembled, which can be packed within a small compass, one member 30 of said board being provided with a checker-board upon its reverse side.

These and other objects may be attained by means of the construction illustrated in the accompanying drawings, in which:

Figure 1 is a perspective view of the game board made in accordance with my invention, and showing the game pieces set up in position for starting the game, and the cues lying upon the cushions in position for operation. Fig. 2 is a central vertical section of the same. Fig. 3 is a side elevation of one of the pins. Fig. 4 is a similar view of another pin. Fig. 5 is a like view of the other pin, used as accessories in the game. Fig. 6 is a 40 side elevation of one of the balls used in the game. Fig. 7 is a similar view of the other ball. Fig. 8 is a view of one of the pin spots in the table. Fig. 9 is a similar view of another pin spot. Fig. 10 is a like view of 50 the other pin spot. Fig. 11 is a top plan view of the lower member of the game board. Fig. 12 is a bottom plan view of the same.

Referring to the drawings for a more particular description of my invention, the 55 numeral 1 designates the substantially rec-

tangular upper member of the game board provided with a marginal flange 2 having a rubber strip or cushion 3 secured to its inner side. A concaved pocket 4 is provided at the center of the table 1 and extending 60 through said pocket is a tubular discharge opening 5. Indicated upon the upper surface of the table 1 is a series of parallel lines 6, 7, and a number of pin spots 8, said pin spots being numbered to conform to the numbers 65 of the pins. The corner spots are numbered 2, the central side spots are numbered 3, and the four spots at diametrically opposite points around the pocket 4, are numbered 5, to correspond with the numbers of the pins resting on said spots, as shown in Fig. 1 of the drawing.

The pins 9 are shown in Figs. 3, 4, and 5, and may consist of the ordinary pool pins having the various designating numbers thereon. The balls may be differently colored, the cue ball 10, as shown in Fig. 6, being preferably red, and the object ball 11, shown in Fig. 7, being of yellow or some other distinguishing color. Underneath the upper board 1 is a lower board 1^a, said board having a central dome-shaped projection 12, and inclined chutes 13 which extend from said projection 12 outward to the four side edges of the board within reach of the players. The projection 12 is surrounded by a flange 14 which will prevent the balls from rolling over the sides of the chutes or troughs 13. The dome 12 is secured to the upper surface of the board 1^a at a central point immediately 90 under the discharge tube 5 of the pocket 4, as shown more particularly in Fig. 2. The boards 1 and 1^a are spaced apart a sufficient distance by means of corner posts 15, and the boards are detachably connected together by 95 means of hooks 16 connected by a screw eye 17 to the board 1^a, and to an eye 18 on the board 1. Any suitable number of these hooks may be employed. On the lower surface of the board 1^a a checker-board 2^a may 100 be provided in order that this member of the game board may be utilized as a checker-board whenever required.

The game may be played as follows: The pins being set up on the table 1, as indicated in Fig. 1, one of the players takes a cue 3^a and places the red cue ball 10 anywhere outside of the central square on the table, and the yellow or object ball outside the line 6. The player names the pin he will shoot at, and if 110

he knocks it over, the value of the pin will be added to his credit and he is entitled to another shot. He continues until he fails to knock over the pin he has indicated when it is the other player's turn to shoot. If the cue ball rebounds and knocks over any other pin or pins on either side of the board, and he has made the pin he shot at, the value of such pin or pins is added to his credit. If he should fail to make the pin he shot at and the ball rebounds and knocks over any other pin or pins, the latter will be set up again on the places marked on the board, and he receives no credit therefor. If the player hits the yellow ball and also knocks down the pin he shoots at, again the value of the pin and also the value of the ball (five points) will be added to his credit. In other words, if he makes a carom on the object ball and pin he is entitled to the number given on said ball and pin. If one of the balls rolls into the center pocket 4 it is caught by one of the troughs 13 depending upon chance, and rolls out toward one of the players, and this player is entitled to the credit of the five points marked upon the ball. If a pin should be knocked into the pocket 4 it must be again set up in its proper place. If the yellow ball is knocked off of the board, the next player shoots, and the player who knocks the ball off the board receives no credit even if he does knock over the pin he shot at. The object ball 11 is permitted to roll wherever it may and is not touched by hand unless it should roll into one of the troughs 13 when it may be spotted outside the line 6 by the player who receives it.

It will be obvious that the rules of the game may be varied to considerable extent, depending upon an agreement between the players.

From the foregoing it will be obvious that a game made in accordance with my invention will require considerable skill in becoming proficient, that there is sufficient chance in the game to render it entertaining and amusing, that the game may be produced at comparatively slight cost, and can be packed within a comparatively small compass.

Having thus described the invention, what I claim is:

1. A game board comprising an upper member having cushioned flanges, a central concaved pocket having a discharge opening, and a lower member having inclined troughs, and a central dome or deflector, pins and balls adapted to be placed upon the table and operated by cues, substantially as described. 50

2. A game board comprising a rectangular upper member having field lines marked thereon, and a central concaved pocket having a discharge opening therein, numbered spots and similarly numbered pins for said spots, an object ball and a cue ball, and a lower table having a central dome or deflector and inclined troughs, substantially as described. 60 65

3. A game board comprising an upper member having cushioned flanges, a central concaved pocket having a discharge opening therein, and a lower member having outwardly inclined troughs, and a central dome. 70

4. A game board comprising an upper member provided with marginal cushions and a central concaved pocket having a discharge opening therein, and a lower member provided with outwardly inclined troughs or runways, corner posts between said members, and hooks for securing said two members together. 75 80

5. A game board comprising an upper member having marginal cushions, a central concaved pocket having a discharge opening therein, field lines and numbered spots, a lower member spaced from the upper member and provided with troughs or runways inclined from the center outward, a central dome or deflector, a flange surrounding said deflector, means for securing said two members together, numbered pins, a cue ball and an object ball of different colors and numbers, substantially as described. 85 90

In testimony whereof, I affix my signature in presence of two witnesses.

WALTER W. KOHLER.
